UNITED STATES PATENT OFFICE.

WILLIAM F. WOLLIN, OF LANCASTER, AND ELMER H. WERLINE, OF WILLIAMSPORT, ASSIGNORS OF TWO-THIRDS TO HARRY B. COCHRAN, OF LANCASTER, PENNSYLVANIA.

INCANDESCENT ELECTRIC-LAMP SOCKET.

SPECIFICATION forming part of Letters Patent No. 393,733, dated November 27, 1888.

Application filed September 24, 1887. Serial No. 250,565. (No model.)

To all whom it may concern:

Be it known that we, WILLIAM F. WOLLIN, of Lancaster, in the county of Lancaster, and ELMER H. WERLINE, of Williamsport, in the 5 county of Lycoming and State of Pennsylvania, have invented certain new and useful Improvements in Incandescent Electric-Light Lamp-Sockets; and we do hereby declare the following to be a full, clear, and exact description of the invention, such as will enable others skilled in the art to which it appertains to make and use the same.

Our invention relates to new and useful improvements in incandescent electric-light 15 lamp-sockets of the class commonly known as "night-lamp sockets."

The object of our invention is to make a socket to vary the intensity of the light emanating from an incandescent electric lamp, 20 which shall be compact and cheap, and that may be readily used in dwellings, where it is often desirable to diminish the amount of light without extinguishing it. We are well aware of the fact that numerous devices have 25 already been invented for this purpose; but in these inventions the sockets have been bulky, or two lamps and two keys have been necessary, which makes it much more troublesome to manipulate. With our socket we use 30 but one lamp and one key and do away with the series of resistance-boxes used in some of these sockets.

Our invention will be best understood by reference to the drawings which accompany 35 this specification, in which similar letters refer to similar parts throughout the several views.

Figure 1 is a side view of the Edison lamp-socket with the cover removed, showing our 40 invention as applied to this socket when the light is turned on at full head. Fig. 2 is a similar view, the light being turned off. Fig. 3 is a similar view, the light being diminished. Fig. 4 is a plan view of the socket. 45 Fig. 5 is a horizontal section taken through the binding-screws. Fig. 6 is an enlarged detail view of the binding-screws J' and J^2 , the sheet which insulates them from each other, the resistance-plate, and the circuit-closing

springs. Fig. 7 is a detail view of the circuit-controller. Fig. 8 is a similar view of the fixed sleeve. Fig. 9 is an elevation of the complete socket.

A designates the globe of the lamp, having its bottom closed by a brass cup, a .

B designates the incandescent thread or wire within this globe for illumination by incandescence.

C designates a tubular case or neck of sheet metal, spirally grooved to receive a threaded 60 collar, x , which holds the external shell, y , in place.

D designates the metal frame of the lamp-socket, having an inwardly-extending sleeve, d , rigid with its side. The inner end of this 65 sleeve is provided with an oblique groove, d' , having curved recesses or seats 1, 2, and 3 formed in its outer wall, these seats being successively farther from the outside of the frame C in the order named. A circuit-controller, 70 E, in the form of a cylindrical rod, with a handle, e , outside of the frame and casing, turns axially in said fixed sleeve, and has a stud, E', working in said groove. The obliquity of said groove gives longitudinal motion to said circuit-controller as the latter is turned, and said stud engages with any one of the seats or recesses 1 2 3, to hold the circuit-controller temporarily in any one of the positions of inward adjustment. The tip e' of this circuit-controller is of non-conducting material and bears 75 against a curved spring, F, which is attached to a plate, f , rigid with frame D, but separated therefrom by a non-conducting disk, G, at the top of said frame. This spring extends up 80 through a slot, g , in said disk G to a point just below the metal cup a . Its contact with this cup is essential to complete any electric circuit within the lamp. In its normal position this contact is not made and the lamp 85 does not operate. This is its condition when the stud E' is in seat 1, as shown in Fig. 1; but by turning the circuit-controller E until the stud e reaches the seat 2 the spring F is forced back into contact with the cup a . A 90 wire, I, being one of the main-circuit wires, is attached by a binding-screw, J, to a metal lug, j , extending downward from said non-

conducting disk G. A metallic screw, j' , (shown in dotted lines in Fig. 1,) extends upward through said disk from said lug to the metallic tubular case C.

- 5 The plate f is provided with a lateral lug, f' , having a binding-screw, J' , for holding one end of a wire, I' . The other end of said wire is attached to a metallic plate, N, by a binding-screw, J^2 . This plate is attached to disk G, 10 and is similar to plate f , already mentioned, but has no electric communication therewith except through wire I' . The middle part of this wire is wound to form a resistance-coil, α , for which any other suitable resistance may 15 be substituted. The other main-circuit wire, I^2 , is connected to post N by the said binding-screw J^2 .

When the stud e is in the seat 2, as above described, an electric circuit is established 20 from the main wire I , through lug j , screw j' , case C, to incandescent wire B, one end of which is in contact with said case, and cup a in contact with the other end of said incandescent wire; thence through spring F, plate f , lateral lug f' , and resistance-wire I' to the other main-circuit wire, I^2 .

K designates a supplemental closing spring shorter than F and arranged directly behind it. The upper end of this spring is arranged 30 to be forced back against a conducting-plate, L, when sufficient pressure is applied. This plate L is attached to plate f , but insulated therefrom by a non-conducting sheet, M. Plate L is connected to plate N by a laterally 35 extending thread, l , of metal.

When the stud e is in seat 2, as aforesaid, the pressure on spring K is not sufficient to make a contact between it and plate L; but when the circuit-controller E is turned, so as 40 to move the stud e from recess 2 to the recess 3, nearer the center of the lamp-socket, there is necessarily a corresponding inward motion of said circuit-controller, and the upper end of spring K is forced against plate L. 45 Two circuits are then open, the one before described and the one through wire I' , lug j , screw j' , case C, wire B, cup a , and spring F to spring K, which is permanently in contact therewith; thence through plate L and metal- 50 lic thread l to lug N and the main-circuit wire I^2 . As this latter circuit avoids the resistance-

wire I' and its coil α , it is the line of least resistance and will be that followed by the electric current. The lessening of resistance will increase the brilliancy of the light, so that 55 when the stud e is in its most inward seat, relatively to the center of the socket, the light will be at its maximum. The seat is marked 3 on the present drawings; but additional intermediate degrees of brilliancy may be provided 60 for, requiring an increase in the number of seats.

Having thus described our invention, what we claim as new, and desire to secure by Letters Patent, is—

1. In combination with a grooved fixed sleeve having seats 2 and 3, a circuit-controller, E, having rotary and longitudinal motion therein and provided with a stud adapted to occupy at will either of said seats, and moving from one to the other in the groove of said sleeve, two springs arranged the one behind the other in front of the inner end of said circuit-controller in order that one spring only may be forced back when the stud of the 75 circuit-controller occupies seat 2, but both springs may be forced back when said stud occupies seat 3, metallic parts which make contact with said springs when thus forced back, and conductors forming circuits of different 80 degrees of resistance which are closed by such contact, substantially as set forth.

2. The circuit-controller E, having stud e' , in combination with a fixed grooved sleeve having seats 1, 2, and 3, arranged as shown, 85 the circuit-closing springs F and K, the plate L, arranged for contact with the latter, a cup, a , arranged for contact with spring F, the three wires I I' I^2 , and the electric connections between them and the other parts above 90 stated, making at will the circuit through the resistance-wire I' , or the circuit independent of said wire I' , as set forth.

In testimony whereof we have hereunto subscribed our names in the presence of two sub- 95 scribing witnesses.

WILLIAM F. WOLLIN.
ELMER H. WERLINE.
